UNITED STATES PATENT OFFICE.

ELMER L. RUSSELL, OF CLEVELAND, OKLAHOMA.

AEROPLANE.

1,160,768.

Specification of Letters Patent. Patented Nov. 16, 1915.

Application filed May 20, 1913, Serial No. 768,700. Renewed September 30, 1915. Serial No. 53,424.

To all whom it may concern:

Be it known that I, ELMER L. RUSSELL, a citizen of the United States, and a resident of Cleveland, in the county of Pawnee and State of Oklahoma, have made certain new and useful Improvements in Aeroplanes, of which the following is a specification.

My invention relates to improvements in aeroplanes and it consists in the combinations, constructions, and arrangements herein described and claimed.

An object of my invention is to provide a device in which the elevating or lowering planes may be readily controlled.

A further object of my invention is to provide a device in which the tendency to tip to the side is obviated by means of a novel arrangement of ailerons.

A further object of my invention is to provide novel means for operating these ailerons.

Other objects and advantages will appear in the following specification and the novel features of the device will be particularly pointed out in the appended claims.

My invention is illustrated in the accompanying drawings forming part of this application in which similar reference characters indicate like parts in the several views and in which—

Figure 1 is a side view of the device, Fig. 2 is a front view thereof, and Fig. 3 is a plan view of the device.

In carrying out my invention I provide a main frame consisting of the uprights 1, 2, 3, 4, 5, 6 and 7, the cross members such as those shown at 8 and the longitudinal members such as those shown at 9, 10 and 11 in Figs. 1 and 3. The device is also suitably braced by guy wires. Carried by the frame at the front end thereof is a front elevating plane P which is pivoted on one of the cross members 8 as shown in Fig. 3. A plurality of sustaining planes S is arranged to extend between the uprights 3 and 4 (see Fig. 1). These planes S are arranged one above another. The rear edges of the planes are disposed below the front edges and the planes themselves are curved slightly as indicated in the drawing. The engine E is carried by the frame below the lowermost sustaining planes. While I have shown four of these sustaining planes, it will be understood that more or less may be used without departing from the spirit of the invention.

Carried by shafts 12 are the propellers T and T'. These propellers are driven by sprocket chains 13 carried by a sprocket wheel 14 of the engine (see Fig. 2) and arranged to run over sprockets 15 on the shafts 12. The propellers are located immediately behind the sustaining planes as shown in Fig. 1 and at the side of the frame as shown in Fig. 2.

Hinged to one of the rear cross members 8 is an elevating plane R. A stationary horizontal plane Q is disposed between the side members 10 and the rear member 8 to which the plane R is hinged. The front edge of this stationary plane Q is cut away at its central portion q to provide room for a vertical rudder W which is hinged at w to one of the cross members 8 as shown in Fig. 3. Four ailerons of the shape shown in the drawings are secured to the uprights 8, these ailerons being placed near the top and near the bottom of the machine. In Fig. 1 I have designated the top aileron as A' and the bottom aileron which is beneath the aileron A' is designated as A². On the opposite side of the center of the machine are the upper and lower ailerons A³ and A⁴ respectively.

The pilot's seat M is carried on the lower part of the frame. A steering rod O is mounted on a universal bearing or pivot o. One end of the steering rod is connected with the elevating rod P by means of a rigid rod X. A flexible cord or cable 17 is connected to a swivel ring 17^x or other similar device on one end of the steering rod O and passes around a pulley 18, thence rearwardly over a pulley 19 to the rear of the elevating plane R. A flexible cord or cable 20 is secured to a swivel ring 20^x carried by the steering rod O on the opposite side of the universal pivot o and passes over a pulley 21 and thence around a pulley 22 at the rear of the device, being connected to the end of the plane R on the opposite side from the cord 17. It will be apparent that when the wheel K of the steering rod is lowered a thrust will be transmitted to the rigid rod X thereby rotating the elevating plane P, so as to incline its front edge downwardly and the rear edge upwardly, while the rear edge of the plane R will be swung downwardly. The control of the machine as far as vertical movement is concerned is thus effected by means of the steering rod.

Hinged to the bottom portion of the device is a foot lever 23 which may be operated by the left foot of the aviator, a similar foot lever 24 being provided for the right foot. As will be seen from Fig. 2 a cord 25 is secured to the foot lever 23, passes around a pulley 26 on the lower portion of the frame, thence upwardly around a pulley 27 and is fastened to the upper aileron A'. A similar cord 28 passes around a pulley 29 on the bottom of the frame, thence upwardly around a pulley 30 and is fastened to the aileron A³. The ailerons A' and A³ are pivotally connected by a rigid rod 31. A cord 32 is connected with the foot lever 23 and thence passes backwardly and upwardly being connected to the lower aileron A⁴. A similar cord 33 is connected to the foot lever 28 and passes backwardly and upwardly being connected to the aileron A². The lower ailerons A² and A⁴ are pivotally connected by a rigid rod 34.

It will be observed that when the foot lever 23 is pressed forwardly by the left foot the rear ends of the ailerons A' and A³ will be swung to the right, (considering the position in which the aviator faces), while the rear parts of the lower ailerons A² and A⁴ will be swung to the right. On the other hand if the foot lever 24 is pressed forwardly the four ailerons will be swung in the opposite direction from that attained by pressing forwardly on the foot lever 23. The aviator has his feet on these foot pedals all the time, and as one foot pedal swings forward the other will necessarily swing back due to the fact that the rigid rod between the ailerons will transmit the movement of one foot lever to the other.

Referring now to Fig. 2 it will be seen that the steering rod O is provided with a cross bar W'. To one end of this bar is secured a spring w' which is fastened to a cord 35. The latter extends over a pulley 36 (see Fig. 2) thence rearwardly and downwardly and is connected to a cross bar 37 which is attached to the rear vertical rudder W. The opposite end of the cross bar W' is connected to a spring w² which is attached to a cord 38 which passes upwardly over a pulley 39 thence downwardly and rearwardly and is secured to the opposite end of the cross arm 37. As has been before stated the steering rod O is mounted on a universal joint so as to permit the rotation of the rod around its own axis. By rotating the steering wheel K the vertical rudder W may be shifted to the right or to the left. The purpose of the springs w' and w² is to prevent a movement of the rudder W when the steering post is being shifted around its pivot O

to manipulate the front and rear elevating planes P and R respectively. The point at which these springs are attached is comparatively near the universal pivot o so that the movement of the steering rod at this point is slight as compared with the movement of the rod at the points where the cords 17 and 20 are attached. The rotation of the rod, however, is sufficient to cause one spring to be tightened and the other spring to give and thereby cause the vertical rudder W to move in response to the movements of the wheel.

The device, as described above, may be readily manipulated so as to cause the downward or upward movements or the movement of the device to the right or to the left. The wheels 40 permit the device to be started easily from rest and to run along the ground when descent is made thereby obviating danger of injury to the machine.

I claim:—

1. In an aeroplane, a main frame, a front and a rear elevating plane, a vertical rudder, a steering post, a universal bearing for pivotally mounting said steering post, swivels carried by said steering post on opposite sides of said universal bearing, a rigid connection between one of said swivels and said front elevating plane, flexible connections between both of said swivels and said rear elevating plane for operating the latter, a cross bar carried by said steering post, cords secured to each side of said vertical rudder and extending forwardly, pulleys carried by the frame for receiving said last named cords, and a spring secured to each end of said cross arm and connected at the opposite end with one of said cords.

2. In an aeroplane, a main frame, a front and rear elevating plane, a vertical rudder, a steering post, a universal bearing for said steering post, swivels carried by said steering post on opposite sides of said universal bearing, a rigid connection between one of said swivels and said front elevating plane, flexible connections between both of said swivels and said rear elevating plane for operating the latter, a cross-bar carried by said steering post, cords secured to each side of said vertical rudder and extending forwardly, and means disposed between the ends of said cords and said cross-bar for permitting a pivoted movement of the steering rod in a vertical plane while the vertical rudder is stationary.

ELMER L. RUSSELL.
